UNITED STATES PATENT OFFICE.

JACOB MEYERHOFF, OF CHICAGO, ILLINOIS.

TELEPHONE SIGNAL SYSTEM.

1,093,794.

Specification of Letters Patent. Patented Apr. 21, 1914.

Application filed November 15, 1912. Serial No. 731,491.

To all whom it may concern:

Be it known that I, JACOB MEYERHOFF, a citizen of the United States, and a resident of the city of Chicago, county of Cook, 5 and State of Illinois, have invented certain new and useful Improvements in Telephone Signal Systems, of which the following is a specification.

My invention relates to telephone signal 10 systems and has for its object the provision of an improved telephone signal system by means of which connections may be obtained without conversation with the exchange operator, thus saving time and avoiding mis- 15 takes due to misunderstandings as to the connection desired.

The invention consists in the combinations and arrangements of parts hereinafter described and claimed.

20 The invention will be best understood by reference to the accompanying drawings forming a part of this specification, and in which,

Figure 1 is a front elevation of an ex- 25 change signal board employed in carrying out my invention, Fig. 2, a section of a desk board for use by each user of the system, Fig. 3, a diagrammatic view illustrating the circuits employed in conjunction with each 30 telephone instrument in the system, and Fig. 4, an enlarged section taken on line α — α of Fig. 3.

The preferred form of construction as 35 illustrated in the drawings comprises a signal board 10 having a plurality of individual electric lights 11 arranged thereon one above the other and numbered to correspond with each telephone instrument in the system. Opposite each of the lights 11 is ar- 40 ranged a plurality of numbered lights 12, said lights being numbered, as indicated for convenience in indicating the instrument with which connection is desired. Inasmuch as the system illustrated is designed for use 45 especially at private exchanges, I provide an additional signal light 13 for each individual light 11 and label such additional light 13 with the letter C to indicate that a connection with the central exchange is de- 50 sired. Each telephone instrument in the system is provided with a spring-actuated receiver supporting lever 15 which is connected by means of wires 16 in circuit with the corresponding individual light 11, as in-

dicated in Fig. 3, said connection being such 55 that when the receiver of the instrument is supported on the lever, the circuit through the corresponding light 11 will be broken and when said receiver is removed from said lever, said circuit will be closed and the cor- 60 responding individual light 11 lighted, as will be readily understood. A desk block 17 is provided to be used in conjunction with each telephone instrument, said desk block being provided with a plurality of spring- 65 held push buttons 18 labeled to correspond with the electric lights 12 and 13 on the exchange signal board. Each of these push buttons 18 is provided at its lower end with a metallic or magnetic head 19 and an elec- 70 tro-magnet 20 is arranged in block 17 and provided with an armature plate 21 positioned immediately under heads 19. Armature plate 21 of each block 17 is connected by means of a wire 22 with each of the cor- 75 responding lights 12 and 13, and each of said lights 12 and 13 is in turn connected by an individual wire 23 with the head 19 on the correspondingly labeled button 18 of the corresponding block 17. Electro-mag- 80 net 20 is connected by means of wires 24 and 25 in series with the corresponding light 11 and receiver supporting lever 15, as indicated in Fig. 3.

In use, when it is desired to make connec- 85 tion with another instrument, the receiver is first removed from the receiver supporting lever 15 as is usual. This closes the circuits through the corresponding light 11 and the electro-magnet in the corresponding 90 block 17. Then the user presses the push buttons 18 corresponding with the number of the instrument with which connection is desired. Depression of said buttons closes the circuits for the corresponding lights 12 95 and 13 by bringing the corresponding head 19 in contact with plate 21. Electro-magnet 20 having been excited by the previous clo- 100 sure of the exciting circuit therefor, each depressed button is held depressed by the magnetism in plate 21, thus when the receiver is first removed from the receiver supporting instrument, the exchange operator is notified that connection is desired for that instrument by the lighting of the cor- 105 responding light 11. Immediately afterward the connection desired will be indicated by lights 12 or light 13 and the con-

nection can be made without any conversation passing between the user and the exchange operator. When the receiver of the instrument with which connection is desired is removed from its supporting lever, the corresponding light on the exchange board is lighted, thus showing the exchange operator that the call has been answered. When the conversation is terminated, and the original caller hangs up his receiver, the circuits through the corresponding electro-magnet, 20 and corresponding light 11 are broken and the corresponding light 11 goes out. Breaking of the circuit through electro-magnet 20 releases any push buttons which are held in depressed positions by the magnetism thereof and these push buttons return to original positions thus breaking the circuits for the corresponding numbered lights 12 or light 13 and thus placing the system in its original or normal condition.

It will be observed that all calls or connections can be made by use of this system without any conversation whatever passing between the user and the exchange operator, thus greatly facilitating the making of such connections and lessening the chances for error and waste of time therethrough.

While I have illustrated and described the preferred form of construction for carrying my invention into effect, this is capable of variation and modification without departing from the spirit of the invention. I, therefore, do not wish to be limited to the precise details of construction set forth but desire to avail myself of such variations and modifications as come within the scope of the appended claims.

Having described my invention what I

claim as new and desire to secure by Letters Patent is:

1. A telephone signal system comprising an individual electric light and a plurality of numbered electric lights for each telephone in the system; a receiver supporting lever connected in circuit with each of said individual lights to control the same; and electrical circuits under the control of the user and said receiver supporting lever for lighting said numbered lights, substantially as described.

2. A telephone signal system comprising a signal board equipped with an individual electric light and a plurality of numbered electric lights for each telephone instrument in the system, each of said telephone instruments being provided with a spring-actuated lever supporting the receiver proper, said lever being connected in circuit with said individual light so that removal of said receiver closes said circuit; a plurality of circuits for lighting said numbered lights; a plurality of spring-held push buttons adapted to close said circuits; an electro-magnet arranged to hold said buttons in closing positions; and an electric circuit for exciting said magnet, said circuit being connected to be made or broken by said receiver lever, substantially as described.

In testimony whereof I have signed my name to this specification in the presence of two subscribing witnesses.

JACOB MEYERHOFF.
